Benjamin Franklin Adams
Petition Patent

The subscriber referred to in this Petition and making part of the same containing a description in the words of the said Benjamin Franklin Adams himself of his improvement, being an apparatus for steering vessels called Adams' Steering Horizontal Quadrant wheels.

Be it known that I Benjamin Franklin Adams of Boston in the County of Suffolk in State of Massachusetts have made an improvement in the useful art, being an apparatus for steering vessels, called Adams' Steering horizontal quadrant wheels, which is described as follows: reference being had to the annexed drawing. This steering apparatus consists of the following principle parts. The rudders with the wheel, rope and blocks, the steering horizontal wheels, resting on an arbor, the steering quadrant, For double steam and hand-boats I use two rudders A.B. instead of one placed parallel and side by side at the stern of the vessel. Each of these rudders need only be of about half the area or surface of the common rudder. It will have much more power to turn the vessel, yet not impede its head way more than one half, for the impeding of this vessel's head way is as the cubes of the areas of each rudder taken separately; another D. is fixed on the head (i. e. of the rudder to prevent the said rudder wearing out. In any convenient part of the vessel place uprights B.B. with a cross piece E. to receive an arbor G. upon which the horizontal steering wheels turn. There are three horizontal steering wheels H.P.H. placed upon the before mentioned arbor, each having a groove in its periphery to receive a chain or a band. In the upper and lower wheels are fixed any convenient number of pins I. pointing towards the centre wheel. In the centre wheel are provided

made to receive three pins, by means of which pins on the upper and lower ^{wheels}, and the holes in the centre wheel, the wheels are made to disengage and the rudder steered in different directions. A steering quadrant is made of every metal, having a groove in its rim, is supported only when on a pin between an upright ls. Having a slot or opening in it the steering rope, chain or handle which passing round the steering horizontal wheels is fastened in the groove of the quadrant. Six handles for steering are fixed on the periphery of the quadrant, 3 Operation, 3 one or two handles being placed at the steering quadrant, steer the rudder in the usual way, say, in a direct course.

When it is required to go in a contrary direction or backward then the centre wheel is attached to the upper wheel by pins and held and sliding up and down the axle, this enables the steers man to go in a contrary direction. What I claim as my invention and desire to be secured by Letters Patent is the before described horizontal steering, notably by which the direction of a vessel can be changed by the shifting wheels, and the quadrant for steering the rudder.
